LATCH MECHANISM

Albert F. Lickteig, Jr., Grand Rapids, Mich., assignor, by mesne assignments, to Harloc Products Corporation, a corporation of Connecticut

Application June 3, 1948, Serial No. 30,755

9 Claims. (Cl. 292—244)

1

This invention provides a door latch mechanism which may be installed without regard to the direction in which the door will swing. The characteristics of the conventional door latch are such that it is adapted to engage a striker plate from one direction only. As a result of this, the usual practice for the installation of these devices is to assemble them to the door at the time the door is hung in place. It is usual to provide such devices with a cross bar equipped with knobs or handles to actuate a retracting mechanism which serves to withdraw the bolt from locking position. When these cross bars or equivalent members have once been installed, it is no longer possible to rotate the entire latch mechanism within its recess in the door. For these reasons, the installation of lock mechanisms in doors has been left entirely in the hands of the carpenter on the job, which is considerably more costly than would be the case if the lock mechanism could be installed by the manufacturer of the doors at a station on a production line.

A latch embodying the present invention may be installed in a door at the factory where the door is made. The adaption of the latch to a particular door installation is preferably accomplished by the application of a minor part to the exterior of the lock mechanism by the workman on the job. The application of this part merely serves to select which side of the bolt is to operate as a locking surface, the other side of the bolt serving as a ramp causing the bolt to retract when the door is pushed to a closed position.

To open a door which is provided with a conventional latch, it is necessary to rotate the knob sufficiently to completely withdraw the bolt into the recess provided for it. When one is in a hurry, it may be burdensome to be forced to completely actuate the knob through its entire travel; and it may also be extremely difficult to do so if one happens to be carrying packages or other articles which interfere with the use of the hands. The present invention, however, has provided an arrangement for supporting the bolt in locking position only when the bolt is at or near the outward extremity of its movement. When the hand operated actuating system has caused the bolt to be slightly withdrawn from its locking position, the supporting means ceases to be effective, and permits the bolt to be rotated slightly by a force tending to open the door. This slight rotation causes the locking surface to assume a slant position, and to then act in much the same way as the opposite face of the lock when the door is pushed closed. The force of the striker plate

5 against a bolt which has assumed this position provides a force tending to urge the bolt inwardly and thereby permit the door to be pulled to an open position before the actuating mechanism has completely retracted the bolt into its recess.

10 The mechanism which provides these general characteristics includes a bolt which is adapted to travel from a locking position to a retracted position, and return, within the confines of a passageway. At the outer extremity of this passageway a supporting structure is located which is in position to engage particular clamping surfaces upon the bolt as the bolt is urged outwardly into locking position by the action of suitable biasing means. These supporting surfaces are preferably 15 parallel to the passageway, at least one of these supporting surfaces being relatively short with respect to the axis of this passageway in order that the bolt may be released from the combined 20 effect of the support surfaces when the bolt has been retracted a short distance from its normal locking position.

25 The preferred form of this invention provides a bolt which is symmetrical in form, and has an outwardly converging locking portion. It is preferred that the bolt be generally rectangular in cross section, with the converging characteristics accomplished by forming the bolt with two opposite sides lying along intersecting planes. The 30 remaining two sides of the bolt are parallel. The angle of intersection of the aforementioned two planes has been found to be preferably in the neighborhood of 45 degrees.

35 The bolt, in its simplest form, is also provided with another pair of surfaces, each of which cooperates with one of the converging surfaces mentioned above. These cooperating surfaces are so placed relative to the locking surface that a clamping action is possible between them which creates the necessary locking rigidity when these 40 surfaces are engaged by the support means at the outer extremity of the bolt passageway. It is of course necessary that an auxiliary clamping surface which is to cooperate with a locking surface 45 must be disposed between perpendiculars to the ends of that portion of the locking surface which is used as a clamping surface. The most convenient form for a bolt which complies with these geometric requirements is to form the auxiliary 50 clamping surfaces parallel with the locking surfaces with which they cooperate, and allow them to intersect the locking surface with which they do not cooperate. This conformity provides a means for guiding the clamping surfaces into engagement with the support means due to the con-

verging qualities of the locking surfaces. As the bolt moves outwardly under the action of the biasing means, the converging portion of the bolt seeks its path outwardly through the passageway and aperture into its proper position, the slope of the locking portion guiding the bolt into a position in which the clamping surfaces will be properly engaged by the support means.

When the bolt has been partially retracted by the manually operated retracting means, it is preferable that a certain amount of rotation be permitted to the bolt in order to present a slant surface to the locking face of the bolt if the door is then being urged to an open position. This restricted rotatability is accomplished by the manner of supporting the bolt within the bolt passageway. Preferably, the bolt slides within the passageway, confined therein by the contact of the outermost portions of the bolt with the walls of the passageway. The two parallel sides of the locking portion may be used as sliding surfaces, or other generally parallel surfaces may be used which are similarly disposed for this purpose. This arrangement of course provides for slideably retaining the bolt in a manner which does not permit a substantial degree of rotation in the plane perpendicular to the two parallel surfaces. A limited degree of rotation is permitted, however, in another plane. This plane in which limited rotation is permitted is perpendicular to the intersection of the outwardly converging locking surfaces. The simplest manner of securing the bolt within the passageway to permit the desired amount of rotation is to provide a bolt which has its maximum width restricted to a very short dimension measured generally parallel to the axis of the passageway. In this manner the bolt is permitted to rotate without being directionally confined by the sides in the same manner as the bolt is confined by the parallel sides. The amount of rotation which the bolt is permitted should be limited so that the bolt may not assume a position in which it does not easily engage the supporting surfaces. It is also preferable that the rotation be restricted to that amount which will not permit a locking surface to form an acute angle with respect to that part of the front plate adjacent thereto. The reason for this latter requirement is to facilitate the passage of the bolt through the aperture of the front plate when the door is slammed shut, causing the bolt to be forced inwardly by the action of the back or slant surface acting against the striker plate of the door jamb.

Since the bolt is acting under the influence of an outwardly biasing means, some measure must be taken to limit the outward movement of the bolt so that it does not advance beyond a locking position. The stop means which is provided for this purpose may either be in the form of shoulders which are disposed upon the sides of the bolt adjacent the clamping surfaces, or may be in the form of a fulcrum support which is disposed generally in the plane of symmetry of the bolt. When the side-type of stop is used, it operates by engaging a portion of the front structure of the lock, which is usually a plate attached to the structure forming the passageway. The contact of such a shoulder with this structure, when combined with the outward force of the biasing means exerted near the central area of the bolt, causes a moment to be created which tends to straighten the bolt so that its plane of symmetry is parallel to the passageway. When a fulcrum type support is used with the fulcrum

substantially on such plane of symmetry, there is no such tendency to straighten the bolt out and the bolt is then free to assume whatever angular position relative to the passageway that exterior forces may urge it into. This latter type of stop means can be effectively combined with a toggle-type of mechanism in a modification of this invention to create an unstable biasing means for the bolt which tends to assist the bolt to assume a position wherein one of the clamping surfaces is parallel to the wall of the passageway. With this type of mechanism, the bolt is caused to snap definitely into a position which it assumes when it engages the supporting surfaces. As a door is pushed to a closed position, the first contact of the striker plate with the bolt causes the bolt to be forced to the position shown in Figure 2, since the force generated by the striker plate tips the bolt to a position where the bolt is in such alignment as to be prepared to engage the supporting surfaces. When a toggle-type arrangement is utilized as above discussed, such alignment of the bolt is rendered positive, the bolt returning to locking position in the generally desired alignment.

This invention will be described by an analysis of the particular mechanisms and components which are illustrated in the accompanying drawings. In these drawings:

30 Figure 1 is a horizontal section through a door which is provided with a latch embodying this invention. The section is taken principally through the case and supporting structure, with the parts and components left in full line.

35 Figure 2 is a section of the same mechanism shown in Figure 1, but in the retracted position.

Figure 3 is a schematic diagram of the forces which are applied to the bolt which permit it to function as a latch.

40 Figure 4 is a top view of the mechanism illustrated in Figure 1 with the upper half of the case removed to show the parts contained. This view may be considered to be in a vertical plane.

Figure 5 shows a mechanism embodying a toggle-action biasing means.

45 Figure 6 is a section along the plane 6-6 of Figure 5, illustrating principally an end view of the cross-head.

Referring to Figure 1, the latch mechanism 10 is shown installed within the bore 11 of the swinging door 12. This installation permits the latch bolt 13 to project outwardly from the surface 14 of the door which closes within the door jamb in order to accomplish the latching function through engagement of said bolt with a suitable striker plate affixed to the jamb. The latch mechanism is generally contained within the case 15 which is comprised of the symmetrical halves 16 and 17. The bore 18 is disposed to permit the passage of a cross bar (not shown in Figure 1) which cooperates with the roll-back members 19 and 20 to effect actuation of the retracting mechanism of the latch.

The general operation of the retracting mechanism can best be described by referring to Figures 1, 2, and 4 together. The roll-back elements 19 and 20 are usually individually operable by cross-bar sections associated with either side of the bore. Rotation of either of these roll-back members in either direction causes the cross head 21 to move to the right due to the engagement of either of cam surfaces 22 or 23 with the outwardly turned ears 24 or 25. The ears 24 and 25 are formed integrally with the tension arms 26 and 27, the tension arms being

structurally attached to the plate 28 which has its surface generally perpendicular to the movement of the cross head. The actuation of the cross head in a direction to the right is opposed by the action of spring 29 which bears against inner surface 30 of the cross head 21. The opposite or right end of the spring 29 is supported by the spring seat 31, which in turn is supported by a shoulder 32 in the case 15.

The outwardly turned ears 24 and 25 not only serve the purpose of engaging the cam surfaces 22 and 23, but also serve to engage the guiding slots 33 and 34 which are located in the vertical surface 35 of the case 15. Preferably the ends 36 and 37 of the slots 33 and 34 are so positioned as to act as limit stops to the movement of cross head 21 through the engagement of the outwardly turned ears 24 and 25 therewith.

The construction of the cross head 21 is preferably an integral piece formed by welding or otherwise attaching two symmetrical halves which are united on a plane which passes through the center of the latch mechanism parallel to the view shown in Figure 4. Figure 4 shows the lower half of the cross head having this type of construction, the upper half being identical thereto and having ears, arms, and surfaces which are in all respects the exact opposite of those shown. The upper half 16 of the case 15 is provided with slots similar to 33 and 34 for the guide and stop purposes previously described. Preferably, the two halves 38 and 39 of the cross head 21 are joined together by a series of spot welds along the tension arms 26 and 27 and their opposite equivalents.

Previous to the joining of the two halves 38 and 39 of the cross head 21, a retracting link 40 is installed within the aperture 41 which is formed in the plate 28 as indicated in Figure 6. Previous to such installation of the link 40, the spring 42 is of course placed in position, since this spring bears against the plate 28 in order to create the biasing force tending to urge the bolt 13 outwardly with respect to the door. The retracting link 40 and the aperture 41 are so proportioned that the link may slide therein and be permitted a small degree of articulation in the plane indicated in Figure 1. With the mechanism indicated in Figures 1 and 4, it is clear that bolt 13 may move inwardly from either of two causes. A striker plate which is intended to cooperate with the bolt may bear upon the slanted surface 43 of the bolt 13 when the door is slammed shut, thereby creating a component of force tending to push the bolt inward against the action of spring 42. It is clear that under these conditions the cross head 21 remains in the position shown, the bolt 13 moving from the position indicated in Figure 1 to that shown in Figure 2. The bolt 13 may also be caused to move inwardly by the action of the hand operated retracting mechanism previously discussed which causes the cross head 21 to move to the right and take with it the retracting link 40, which draws the bolt 13 by means of the pivot connection indicated at 44.

The locking effect of the bolt 13 is best described by reference to the schematic diagram indicated in Figure 3. The biasing means which derives its force from the action of spring 42 may be said to create an outward force 45 which acts at the pivot connection 44. The effect of the force 45 is to firmly place the bolt 13 in engagement with the supporting structure of the lock. It will be noted that the bolt 13 is gen-

erally symmetrical about a plane 46, and that the outer or locking portion of the bolt 13 is formed by the outwardly converging surfaces 47 and 48, together with the parallel surfaces 49 and 50. The type of bolt-supporting structure diagrammed in Figure 3 permits the bolt to be supported against the action of the locking force 51 only when the bolt is in the outer or locking position. As bolt 13 moves inwardly in the general direction indicated in Figure 2, the clamping surfaces of the bolt come out of engagement with the supporting structure, and the bolt 13 no longer has the ability to maintain the alignment shown in Figures 3 and 1. The clamping surfaces of the bolt shown in Figure 3 include the clamping portion 52 of a locking surface 48. The auxiliary clamping surface 53 is disposed to receive force directed at the surface 52. This requires that at least a substantial portion of the clamping surface 53 be positioned between perpendiculars from the ends of the surface 52, thus creating an overlapping relationship. A locking force 51 not only generates a force within the supporting structure to oppose it, but also generates a moment tending to rotate a bolt 13 in a clockwise direction about the point 54, which is due to the fact that the locking force does not act along the same line as a force 55. An opposing moment to that previously described is generated by the cooperation of the rearward portion of the surface 52 with the bolt supporting structure so as to generate a force 56. In general, the combination of forces 51 and 55 will create a clockwise moment, while forces 55 and 56 co-operate to create an exactly equal and opposite moment which permits the bolt to maintain the position shown.

It is of course possible to provide a set of clamping surfaces which are not directly related to the locking surfaces of the bolt, but the simplest and preferred form is that indicated in the various figures of the drawings associated herewith. It will be obvious that the auxiliary clamping surfaces 53 and 57 are respectively parallel to the surfaces 48 and 47, and intersect the surfaces with which they do not cooperate for clamping action. It has been found most desirable to form the bolt 13 so that the angle included between the sides 47 and 48 is approximately 45 degrees. Regardless of such angle it is clear that with suitable modifications of the supporting structure, the bolt 13 may be just as easily supported in a position which is 45 degrees in a clockwise direction from that indicated in Figure 3. The changes in structure required would be simply that the shorter supporting surface 58 and the longer supporting surface 59 would be interchanged.

The structure of the forward end of the latch mechanism illustrated in the accompanying drawings provides for such an interchange of supporting structures to permit the alignment of the bolt with either surface 48 or surface 47 in a position parallel to the general retracting motion of the bolt. In this manner it is possible to adapt the latch mechanism to a door which must swing in either direction even though the latch mechanism has been firmly fixed in place previous to the installation of the door.

Referring to Figure 1 the longer supporting surface designated by 59 in Figure 3 is formed by the surface 60 of the lower half of the case 15. The shorter surface 58 indicated in Figure 3 has its counterpart in the surface 61 which is provided by the front plate 62, and is firmly secured in

position relative to the balance of the latch mechanism through the engagement of the extruded portions 63 and 64 with an inner plate 65, the inner plate being securely attached to the case 15 by the rivets 66 and 67. The plate 62 is held in the position shown in Figure 4 by the action of the woodscrews which secure the latch mechanism in place within the door.

A close examination of plate 62 will indicate that the aperture 68 is eccentric with respect to the mounting portions 63 and 64. Since the surface 61 forms a part of this aperture, it is clear that a rotation of the front plate of 180 degrees in a plane generally parallel to the normal position of the plate will cause the surface 61 to assume the same position with respect to the upper surface 69 of the case that it now assumes with respect to the surface 60, thereby creating a set of supporting surfaces which will engage the auxiliary surface 70 and the surface indicated at 43. With such an alignment, the surface 71, which can be designated as a locking surface in Figure 1, becomes a slanted surface serving the same purpose as is served by surface 43 with the bolt disposed as shown.

As the bolt 13 moves outwardly from the position indicated in Figure 2 to the locking position indicated in Figure 1, the auxiliary clamping surface intercepts the outwardly converging surface and creates a tendency for the bolt to guide itself into engagement with whichever supporting surfaces are then in position. If the bolt may be assumed to be in a position wherein the plane of symmetry is parallel to the axis of the passageway, the smaller supporting surface 61 contacts the surface 43 at some point and tends to urge the bolt 13 into the general position indicated. This alignment of the bolt into a locking position is generally facilitated by the forces which occur during the closing of the door. As the door is slammed shut, the striker plate exerts pressure upon the surface 43, which of course tends to urge the bolt into the locking position shown. As the engaging aperture of the striker plate comes opposite the bolt 13, the bolt naturally tends to snap into engagement therewith in the proper alignment.

It is of course necessary to provide some form of stop means to prevent the action of spring 42 from urging the bolt outwardly beyond locking position. The stop means indicated in Figure 1 comprises the shoulders 72 and 73 which engage the projecting section of the front plate to prevent outward movement of the bolt beyond the point indicated. It is clear that the action of the stop means in cooperation with the biasing force of the spring 42 tends to create a moment upon the bolt tending to rotate it in a clockwise direction. If it is desired to eliminate such a straightening moment, and to render the action of the biasing means somewhat positive with respect to positioning the bolt for either of the two locking positions, the arrangement indicated in Figure 5 may be used. A fulcrum stop as indicated at 74 may be used, and a toggle action biasing means may be used in conjunction therewith to render a positioning action of the bolt more positive. It will be noted that the biasing means is pivotally connected to the bolt at the point 75, and that the fulcrum stop 74 is disposed outwardly therefrom where it contacts the front structure of the latch mechanism at a convenient point. Since the pivots 74 and 75 are generally located upon the plane of symmetry of the bolt, it follows that the toggle action gen-

erated thereby would tend to cause the bolt to snap into either the position indicated, or one in which the bolt is disposed 45 degrees in a clockwise direction from that shown.

As the bolt is being retracted under the influence of the forces generated by a striker plate as is indicated in Figure 2, it is desirable that some means be provided to control the amount of rotation which the bolt may take as it passes inwardly within the confines of the passageway provided by the case 15. The preferred form of the bolt 13 is that in which the outwardly converging surfaces 43 and 71 also act as sliding surfaces as the bolt passes to a retracted position. It is desirable that the bolt not be permitted to rotate beyond a point in which the clamping surfaces are generally disposed to cooperate with the supporting surfaces. To control this rotation, the outer extremities of the bolt may be provided with points which are adapted to engage the surface of the passageway, or special rotation-limiting means such as the abutments 76 and 77 of link 40, may be provided. In either case, it is desirable that in the plane of the bolt indicated in Figures 1, 2, 3, and 5 that the outer extremities of the bolt be short in the general direction in the bolt passageway. The alignment of the bolt in the plane indicated in Figure 4 is maintained without provision for rotation by the action of the link 40 and the parallel surfaces 78 and 79. It is also possible to provide for the alignment of the bolt in that plane simply by the action of parallel surfaces alone, which is particularly simple in the case where the surface 49 and 78 and those of 59 and 79 are in the same plane. This arrangement can be achieved with small modification of the stop system.

Referring to Figure 6, a view is there shown which indicates the construction of the cross-head 21. The upper half 38 meets the lower half 39 along a parting line which includes the locating projections 80 and 81, and the aperture 41. The two halves 38 and 39 are placed together following the insertion of link 40, and the tension arms 26 and 27 are welded to their counterparts 82 and 83.

The particular mechanisms and components shown and described herein are for illustrative purposes only. The features of this invention have now been fully described and are defined by the appended claims.

I claim:

1. In a latch mechanism having retracting means and a bolt with a plurality of locking surfaces, the combination of the following: a front plate; locating means adapted to determine the location of said front plate relative to said mechanism and engageable with said plate in one of a plurality of such locations and means for positioning said bolt to present one of said locking surfaces in locking position comprising an aperture in said front plate, said aperture being eccentric to said locating means.

2. In a latch mechanism having retracting means, the combination of the following: a cross-head having a transversely disposed surface and axially disposed tension arms; a case having a guiding portion for slideably retaining said cross-head; means for inducing inward movement of said cross-head; and spring means opposing said inward movement, said spring means being confined between said tension arms.

3. In a latch mechanism having retracting means, the combination of the following: a symmetrical bolt having outwardly converging lock-

ing surfaces and clamping surfaces parallel to each locking surface, said clamping surfaces being disposed on opposite sides of said bolt from the locking surfaces to which they are parallel and in overlapping relationship thereto; guide means adapted to guide said bolt to and from a retracted position; biasing means urging said bolt outward; stop means preventing outward movement of said bolt beyond a locking position; and support means disposed to closely engage one of said clamping surfaces and the locking surface parallel thereto when said bolt is in a locking position.

4. In a latch mechanism having retracting means, the combination of the following: a symmetrical bolt having outwardly converging locking surfaces and a clamping surface parallel to each locking surface, said clamping surfaces being disposed on opposite sides of said bolt from the locking surfaces to which they are parallel and in overlapping relationship thereto; guide means adapted to guide said bolt to and from a retracted position, said guide means having a front portion adapted to accommodate said bolt in any angular relationship between and including locking positions corresponding to said locking surfaces; biasing means urging said bolt outward; stop means preventing outward movement of said bolt beyond a locking position; and support means having supporting surfaces disposed to closely engage one of said clamping surfaces and the locking surface parallel thereto when said bolt is in a locking position.

5. In a latch mechanism having retracting means, the combination of the following: a symmetrical bolt having outwardly converging locking surfaces and a clamping surface parallel to each locking surface, said clamping surfaces being disposed on opposite sides of said bolt from the locking surfaces to which they are parallel and in overlapping relationship thereto; means forming a passageway disposed to guide said bolt to and from a retracted position, said passageway having a front portion adapted to accommodate said bolt in any angular relationship between and including locking positions corresponding to said locking surfaces; biasing means urging said bolt outward; stop means preventing outward movement of said bolt beyond a locking position; and support means including a front plate having an aperture adapted to closely engage one of said clamping surfaces and the locking surface parallel thereto when said bolt is in a locking position.

6. In a latch mechanism having retracting means, the combination of the following: a symmetrical bolt having outwardly converging locking surfaces and a clamping surface parallel to each locking surface, said clamping surfaces being disposed on opposite sides of said bolt from the locking surfaces to which they are parallel and in overlapping relationship thereto; means forming a passageway disposed to guide said bolt to and from a retracted position, said passageway having a front portion adapted to accommodate said bolt in any angular relationship between and including locking positions corresponding to said locking surfaces; biasing means urging said bolt outward, said biasing means including link means pivotally connected to said bolt on an axis located substantially on the plane of symmetry of said bolt and perpendicular to the direction of retraction thereof; stop means preventing outward movement of said bolt beyond a locking position including abutment means extending from said bolt substantially on the plane of symmetry thereof and in front of said pivot connection; and

support means having supporting surfaces disposed to closely engage one of said clamping surfaces and the locking surface parallel thereto when said bolt is in a locking position.

5. In a latch mechanism having retracting means, the combination of the following: a symmetrical bolt having outwardly converging locking surfaces and clamping surfaces parallel to each locking surface, said clamping surfaces being disposed on opposite sides of said bolt from the locking surfaces to which they are parallel and in overlapping relationship thereto; guide means disposed to guide said bolt to and from a retracted position, said guide means having a front portion adapted to accommodate said bolt in any angular relationship between and including locking positions corresponding to said locking surfaces; biasing means urging said bolt outward; stop means preventing outward movement of said bolt beyond a locking position; support means including a front plate having an aperture adapted to closely engage one of said clamping surfaces and the locking surface parallel thereto when said bolt is in a locking position; and locating means adapted to position said front plate in alternate positions 180° apart in a plane perpendicular to said guide means, said aperture being eccentric with respect to said locating means and disposed so that said alternate positions place the center of said aperture on opposite sides of the axis of said guide means.

8. In a latch mechanism having retracting means, the combination of the following: a symmetrical bolt having outwardly converging locking surfaces and a clamping surface parallel to each locking surface, said clamping surfaces being disposed on opposite sides of said bolt from the locking surfaces to which they are parallel and in overlapping relationship thereto; guide means disposed to guide said bolt to and from a retracted position, said guide means having a front portion adapted to accommodate said bolt in any angular relationship between and including locking positions corresponding to said locking surfaces; biasing means urging said bolt outward; stop means preventing outward movement of said bolt beyond a locking position; support means including a front plate having an aperture adapted to closely engage one of said clamping surfaces and the locking surface parallel thereto when said bolt is in a locking position; and locating means adapted to position said front plate in alternate positions 180° apart in a plane perpendicular to said guide means, said aperture being eccentric with respect to said locating means and disposed so that said alternate positions place the center of said aperture on opposite sides of the axis of said guide means.

9. In a latch mechanism having retracting means, the combination of the following: a symmetrical bolt having outwardly converging locking surfaces, a clamping surface parallel to each locking surface, and each clamping surface intersecting another of the said converging locking surfaces, said clamping surfaces being disposed on opposite sides of said bolt from the locking surfaces to which they are parallel and in overlapping relationship thereto; means forming a passageway disposed to guide said bolt to and from a retracted position, said passageway having a front portion adapted to accommodate said bolt in any angular relationship between and including locking positions corresponding to said locking surfaces; biasing means urging said bolt

outward; stop means preventing outward movement of said bolt beyond a locking position; support means including a front plate having an aperture adapted to closely engage one of said clamping surfaces and the locking surface parallel thereto when said bolt is in a locking position; and locating means adapted to position said front plate in alternate positions 180° apart in a plane perpendicular to the axis of said passageway, said aperture being eccentric with respect to said locating means and disposed so that said alternate positions place the center of said aperture on opposite sides of said axis with one edge of said aperture that is opposite a locking surface in alignment with a side of said passageway.
